FENCE TYING TOOL

Myrtha Moffett, Fresno, Calif.

Application June 29, 1935, Serial No. 29,065

11 Claims.

(Cl. 140—57)

This invention relates to tools for twisting staples and clamping the same about intersecting fence wires to bind such wires together, and particularly represents improvements over the 5 tool and apparatus used in connection therewith shown in my Patent No. 1,903,830, dated April 18, 1933.

The principal objects of the present invention are to provide a tool whose construction and operation is simplified over the previous structure; and to provide a unit for supporting and locating the 10 tool and fence wires in cooperative relation with each other and with the staple to be tied, which is simpler, lighter and easier to manipulate than the unit previously used for this purpose.

These objects I accomplish by means of such structure and relative arrangement of parts as will fully appear by a perusal of the following 15 specification and claims.

In the drawings similar characters of reference indicate corresponding parts in the several 20 views:

Figure 1 is a side view of the tool and supporting unit as in operation.

Figure 2 is a view partly in section of the jaw 25 unit of the tool detached.

Figure 3 is a fragmentary transverse section of the tool on the line 3—3 of Figure 1.

Figure 4 is an end view of the jaws.

Figure 5 is a fragmentary side view of the tool 30 as initially engaged with the supporting unit and staple, the unit being shown in section.

Figure 6 is a plan view of the supporting unit 35 and tool as on the line 6—6 of Figure 5 showing the fence wires and the staple engaged therewith in position to be twisted or tied.

Figure 7 is a view similar to Figure 5 showing the tool arms as swung down to bend the staple 40 legs to position and with the staple as initially engaged with the jaws.

Referring now more particularly to the characters of reference on the drawings, the tool comprises a pair of spaced bars 1 which at and for a certain distance from the rear end are 45 countersunk in and rigidly secured in a block 2 extending lengthwise of and depending from said bars. At their forward end the bars are bent down somewhat sharply as shown at 3, the bottom of the bends being formed as hooks 4 facing

upwardly and rearwardly at an angle to the straight portion of the bars; the tips of the hook 50 portions being rounded. The rear or under faces of the bends 3 above the hook portion are formed with concave saddles 5 for locating engagement

55 with the horizontal fence wire 6 when the tool is in operation, and which wire is then directly above the tip of the hooks 4. Said faces of the bends on their adjacent sides or edges are also formed with recesses or grooves 7 which are concavely curved with the saddle 5 to engage the bent

end or hook portion 8 of a staple, and extending rearwardly therefrom to also engage the adjacent straight portions of the legs 9 of the staple, as clearly shown in Figure 7.

Turnably and slidably mounted in the block 2 5 parallel and centrally between the bars 1 is a barrel 10 whose rear end is provided with a crank handle 11 by means of which it may be manipulated. Slidably fitted in the barrel is a split 10 spring shank 12 held against rotation by a cross pin 13 mounted in the barrel and projecting between the split sections of the shank. Opposed jaws 14 are formed at the forward end of the shank and project outwardly from the adjacent end of the barrel. The outer faces of the jaws 15 at the back are tapered as at 15 to engage the correspondingly tapered jaws of the forward end of the barrel, so that when the shank is retracted in the barrel the jaws will be drawn toward each other. From one end only of the gripping faces of the jaws, lugs 16 project in opposed relation part way across the jaw gap or slot, the spacing between the lugs lengthwise of the jaw face being approximately equal to the outside dimensions between the legs of a staple. The 20 purpose of this will be seen later.

The rear end of the shank is formed as a reduced threaded stem 17, engaged by the tapped hub 18 of a hand wheel 19 disposed adjacent but rearwardly of the crank handle 11. The exterior 30 of the hub is also threaded as at 20 and engages the adjacent tapped portion of the barrel 10. The sets of threads are cut in the same direction (right hand) but the pitch of the threads of the stem 17 is greater than that of the threads 20. 35 By this arrangement, when the hand wheel is turned to the right it will advance into the barrel but at the same time the stem 17 will be drawn outwardly through the hub a greater distance due to the increase in pitch of the threads of the 40 member 17 relative to the threads 20. This will cause the jaws to be retracted into the barrel and drawn together to firmly grip the legs of a staple therebetween.

By making the difference in pitch of the two 45 threads relatively small a very great leverage or clamping pressure may be had without using a large hand wheel, and a very firm grip on the staple legs is thus obtained.

To prevent the hand wheel from being retracted entirely from the stem 17 and from the barrel and also limiting the corresponding advancing movement of the jaw shank from the front end of the barrel beyond a certain limit, a holding screw 21 is mounted in the rear end of the stem 55 17, which projects through to the rear face of the hand wheel and is there provided with a rigid flange 22 overlapping the adjacent end of the tapped bore of the hub 18.

The unit associated with a fence to support the 60

3. A gripping tool comprising a barrel, a split spring shank slidable in the barrel, jaws on the split end of the shank projecting from one end of the barrel, means between the shank and barrel whereby the jaws will be contracted with the longitudinal movement of the shank toward the opposite end of the barrel, a rotary hand member mounted axially of and on said opposite end of the barrel for movement lengthwise thereof, and means between said member and the adjacent end of the shank for moving the latter lengthwise of the barrel with the rotation and longitudinal movement of the member but a lesser distance than that of said member.
4. A gripping tool comprising a barrel, a split spring shank slidable in the barrel, jaws on the split end of the shank projecting from one end of the barrel, means between the shank and barrel whereby the jaws will be contracted with the longitudinal movement of the shank toward the opposite end of the barrel, a rotary hand member mounted axially of and on said opposite end of the barrel for movement lengthwise thereof, and means between said member and the adjacent end of the shank for moving the latter lengthwise of the barrel a certain distance in one direction with the rotation and longitudinal movement of the member a greater distance in the opposite direction.
5. In an apparatus for tying fence wires together by means of staples at the points of intersection of the horizontal and vertical wires of the fence, said apparatus including a tool to twist a staple engaged with the crossed wires; an upright adapted to be disposed behind the fence, a single block slidably mounted on and projecting forwardly from the upright, separate cradles on the block to locate a horizontal wire and the adjacent portion of a vertical wire, means on the block to support and locate a staple in predetermined relation to the located wires, and means on the block to removably locate the tool in position to engage and twist a supported staple.
6. In an apparatus for tying fence wires together by means of staples at the points of intersection of the horizontal and vertical wires of the fence, said apparatus including a tool to twist a staple engaged with the crossed wires; an upright adapted to be disposed behind the fence, a slide block adjustably mounted on and projecting forwardly from the upright, horizontally spaced cradles on the block to support a horizontal wire, a vertical cradle on the block in front of and below said first cradles and centrally therebetween to locate the adjacent portion of a vertical wire, a horizontal web on the block between and below the horizontal cradles and back of the vertical cradle to support a staple in straddling relation to the located wires, and means on said block to engage and locate the tool in operating position relative to the crossed wires and staple.
7. In an apparatus for tying fence wires together by means of staples at the points of intersection of the horizontal and vertical wires of the fence, said apparatus including a tool to twist a staple engaged with the crossed wires; an upright adapted to be disposed behind the fence, a slide block adjustably mounted on and projecting forwardly from the upright, horizontally spaced cradles on the block to support a horizontal
- tal wire, a vertical cradle on the block in front of and below said first cradles and centrally therebetween to locate the adjacent portion of a vertical wire, a horizontal web on the block between and below the horizontal cradles and back of the vertical cradle to support a staple in straddling relation to the located wires, the tool including horizontally spaced bars to straddle the vertical wire and formed with hook portions at their outer ends, and means on the block to releasably engage said elements and locate the tool in an operative position relative to the crossed wires and staple.
8. An apparatus as in claim 7, in which said hook elements and the engaging means on the block are arranged to enable the tool to swivel above the web in a vertical plane about said means as an axis.
9. In an apparatus for tying fence wires together by means of staples at the points of intersection of the horizontal and vertical wires of the fence, said apparatus including a tool to twist a staple engaged with the crossed wires and having horizontally spaced bars adapted at one end to straddle the vertical wire; and formed at said end with downwardly bent portions terminating in hook elements facing upwardly and away from said end, an upright adapted to be disposed behind the fence, a slide block adjustably mounted on the upright and including horizontally spaced walls projecting forwardly from the upright and a horizontal web extending between the walls at their forward end, cradles on the walls adjacent their forward end to support a horizontal wire, a vertical cradle in the forward face of the web centrally between the walls to locate a vertical wire against and in front of the located horizontal wire, the upper surface of the web forming a support for a staple initially engaged with the wires at their intersection, and the under surface of the web being formed with a concave recess extending between the walls to rockingly engage the tips of the hook elements of the tool bars; the space between the back edge of the web and the upright being sufficient to freely receive the downwardly bent portions of the bars.
10. In a fence tying apparatus, means for supporting and locating a horizontal and a vertical fence wire in position for tying comprising an upright adapted to be disposed behind the fence, a slide block adjustably mounted on the upright for movement along the same, cradles on the block in front of the upright to support a horizontal wire at spaced points, and a vertical cradle on the block in front of the horizontal cradles to locate a vertical wire against and in front of the horizontal wire, and centrally between the horizontal cradles.
11. A tool for gripping spaced staple legs comprising jaws spaced apart to receive the staple legs therebetween at right angles thereto, a single lug on one jaw adjacent one end projecting toward the other jaw, and another single lug on the other jaw adjacent its opposite end projecting toward said one jaw; said lugs being spaced apart lengthwise of the gripping faces of the jaws a distance sufficient to receive the staple legs therebetween, and the depth of the lugs being slightly less than the thickness of the staple legs.
